CLAIM

The ornamental design for a round table with a triangular surface pattern, as shown and described.

DESCRIPTION

FIG. 1 is a perspective view of a round table with triangular surface pattern, showing my new design.

FIG. 2 is a side elevational view thereof;

FIG. 3 is a top plan view thereof;

FIG. 4 is a bottom plan view thereof;

FIG. 5 is a bottom plan view thereof with legs in stored position;

FIG. 6 is an enlarged perspective view of a second embodiment of the round table triangular surface pattern;

FIG. 7 is an enlarged top plan view of the embodiment of the round table of FIG. 6; and,

FIG. 8 is a side elevational view along the lines 8—8 of the embodiment of FIG. 7.
